Patented June 20, 1922.

INVENTOR
ALBERT E. KING:

BY

R. S. Morris
Attorney

UNITED STATES PATENT OFFICE.

ALBERT E. KING, OF LOS ANGELES, CALIFORNIA.

BLOWPIPE.

1,420,107.

Specification of Letters Patent. Patented June 20, 1922.

Application filed November 17, 1920. Serial No. 424,775.

To all whom it may concern:

Be it known that I, ALBERT E. KING, a citizen of Canada, residing at Los Angeles, in the county of Los Angeles and State of California, have invented new and useful Improvements in Blowpipes, of which the following is a specification.

This invention particularly pertains to a device for forming flame of various intensities which is especially applicable for use in the manufacture and repair of small articles where heating, soldering, brazing, welding, and similar operations are employed.

15 An object of this invention is to provide a means whereby a flame of different degrees of heat ranging from that of a minute hydrogen gas flame to an intense oxy-hydrogen flame may be readily produced by a single 20 instrument, and the flames of various temperatures gradually increased or diminished where occasion requires.

Another object is to provide a torch or blow-pipe adapted to form a flame of any 25 desired combustible gas and an air jet where a flame of lower temperatures is desired, and to form a flame of the gas and oxygen where a flame of higher temperatures is required.

A further object is to provide a simple and 30 effective valve actuating mechanism whereby the operator of the torch may readily control the flame and vary its temperature with the hand employed in holding the torch and directing the flame so that the other hand 35 may be free to manipulate the article worked upon or otherwise used to facilitate the work.

Other objects will appear hereinafter.

The invention is illustrated in the accompanying drawings, in which:

40 Figure 1 is a view in side elevation of the torch with a portion of the handle removed.

Figure 2 is a view of the torch as seen in vertical section.

Figure 3 is an enlarged detail or inverted 45 plan view as seen on the line 3-3 of Figure 1.

Figures 4 and 5 are details in vertical section showing with Figure 2 the several positions assumed by the valve.

50 Figure 6 is a view in cross section as seen on the line 6-6 of Figure 1.

More specifically, 7 indicates a valve casing which houses a tapered rotary valve 8, and is formed with a series of three separate superimposed passages *a*, *b*, and *c* intersected

by the valve. A nozzle 9 projects from the valve casing and comprises a series of three concentric tubes 10, 11, and 12. The innermost tube 10 forms a duct *d* which leads from the passage *a*, the intermediate tube 11 forms a duct *e* which leads from the passage *b*, and the outer tube 12 forms a duct *f* which leads from the passage *c*. The tubes 10, 11, and 12 terminate at the outer end of the nozzle in tips 13, 14, and 15 respectively; 60 the tip 13 opening just within the open end of the tip 14, and the latter opening just within the open end of the outer tip 15. The outer end of the nozzle is bent downwardly, and the outer tip 15 is formed with 70 an upwardly extending elongated sight member 16 to facilitate aiming the nozzle and pointing the tip at a certain point.

Connecting with the passages *a*, *b*, and *c* are conduits 17, 18, and 19 which are attached 75 to flexible hose 20, 21 and 22 leading from suitable sources of supply of oxygen, air and hydrogen gas respectively.

The valve 8 normally closes the passages *a*, *b*, and *c* to prevent the flow of the oxygen, 80 air and hydrogen to the nozzle, and is provided with a series of ports whereby when the valve is turned to one position hydrogen and air will be permitted to flow into the outer tube 15 and the intermediate tube 14 85 and when turned to another position hydrogen and oxygen will be delivered to the intermediate tube 14 and the inner tube 13 respectively, while the passage *b* is closed to the air. To accomplish the purpose just 90 stated the valve 8 is formed with a pair of parallel superimposed ports *g* and *h* adapted to register with the passages *b* and *c* respectively and to open and close these passages simultaneously, and is formed with 95 a second pair of vertically spaced ports *i* and *j* arranged on a plane extending at an angle to the vertical plane of the ports *g* and *h*. The uppermost port *i* is adapted to open the passage *a* and the port *j* is adapted to open 100 communication between the passage *c* and the passage *b* after the ports *g* and *h* have opened and closed the passages *b* and *c*; the ports *i* and *j* coincidentally opening and closing on rotation of the valve 8. 105

Means are provided whereby the valve may be turned to its various positions and controlled by the fingers of the hand in which the torch is held, which is here shown as embodying a slide bar 23 mounted in a 110

guide-way 24 formed in an extension 25 on the valve casing; the slide bar being fitted with a finger hold 26 by which it may be retracted in opposition to a spring 27. Carried on the slide bar is a rearwardly extending stem 28 having a series of pins 29 thereon adapted to engage notches 30 in a flange 31 formed on the lower end of the valve in such manner that when the slide bar is advanced or retracted the valve will be caused to rotate.

As a means for holding the slide bar in various positions in opposition to the spring 27 a ratchet bar 32 is mounted on the slide bar and extends along the side of the valve casing and is adapted to be engaged by a bill 33 formed on the outer end of the arm 34 of a trip lever pivoted at 35 on the side of the valve casing and acted on by a spring 36 by which the bill is normally maintained in position to engage the teeth of the ratchet bar. The trip lever is provided with a downwardly extending portion 37 fitted with a push button 38 at its lower end by which the lever may be rocked on its pivot to disengage the bill from the ratchet bar. The valve casing and the conduits are encased in a shell 39 formed in the shape of a revolver stock and providing a hand-hold 40 by which the torch may be readily grasped in the hand and held with a finger engaged with the finger piece 26 in such manner that the slide bar may be easily drawn back by pulling on the finger piece much in the same manner as in pulling the trigger of a revolver. The button 38 is disposed on the inner side of the hand-hold where it may be easily depressed by the third or fourth fingers of the hand grasping the stock.

In the operation of the invention, the valve is normally disposed to close the passages *a*, *b*, and *c*, in which position the slide bar and finger piece will be in their outermost positions, as shown in Figures 1 and 2.

When it is desired to produce a flame of hydrogen gas and air the slide bar is drawn back sufficiently to open the ports *g* and *h* to the passages *b* and *c*, as shown in Figure 4, and permit gas and air to flow through the ducts *f* and *e* and be discharged from the nozzle tips 15 and 14 respectively where on being ignited a flame of comparatively low temperature will be formed and the intensity of which may be regulated by varying the extent of opening of the ports *g* and *h*.

The bill engaging the ratchet bar will act to hold the valve in its advanced position, the teeth on the ratchet bar being sufficiently close together to permit the valve being advanced step by step with slight movement so that the ports may be opened little by little and thus permit gradual increase in the intensity of the flame.

When it is desired to produce a flame of

greater intensity than that of the burning hydrogen and air the slide bar is advanced to continue rotation of the valve to close ports *g* and *h* to passages *b* and *c* and open ports *i* and *j* so as to direct the hydrogen gas from the passage *c* to the passage *b* into the duct *e* and out through the nozzle 14 and at the same time open port *i* to the passage *a* to direct oxygen to the duct *d* and out the nozzle tip 13, thus forming a mixture of oxygen and hydrogen at the nozzle tip which on being ignited will form an intense flame, the degree of which may be gradually increased by opening ports *i* and *j* step by step as before described until the ports are fully opened.

When it is desired to turn the valve in retrograde movement the trip lever is disengaged from the ratchet bar by depressing the push button 38, whereupon the spring 27 will act to advance the slide bar 23 on releasing the finger hold 26. By holding the trip lever out of engagement with the ratchet bar, the slide bar may be moved in either direction under the action of the finger and spring so that regulation of the flame may be readily effected.

The volume of the hydrogen, air, and oxygen delivered to the torch may be regulated, of course, by usual control valves, not necessary to be here shown; the control valve of the torch permitting control of the flame and change in the character of the flame by the hand in which the torch is held.

While I have shown and described a specific embodiment of my invention, I do not limit myself to the exact details of construction shown, but may employ such changes in the parts and their arrangement or their equivalents as come within the scope of the appended claims.

I claim:

1. In a blow pipe, a valve casing having a series of three superimposed passages therein, a rotary valve in said casing adapted to close said passage, said valve being formed with parallel ports adapted to open a pair of the passages and formed with a second pair of ports extending on an angle to the plane of the first named ports adapted to open the other passage and form a communication between the other passages, and a nozzle embodying a series of ducts connecting with said passages.

2. In a blow pipe, a valve casing having a series of three superimposed passages, therein, a rotary valve in said casing adapted to close said passages, said valve being formed with parallel ports adapted to open a pair of the passages and formed with a second pair of ports extending on an angle to the plane of the first named ports adapted to open the other passage and form a communication between the other passages, a nozzle embodying a series of ducts con-

necting with said passages, and spring pressed reciprocal means for turning said valve.

3. In a blow pipe, a valve casing having
5 a series of three superimposed passages,
therein, a rotary valve in said casing adapted
to close said passages, said valve being
formed with parallel ports adapted to open
10 a pair of the passages and formed with a
second pair of ports extending on an angle
to the plane of the first named ports adapted
to open the other passage and form a
communication between the other passages,
15 a nozzle embodying a series of ducts con-
necting with said passages, spring pressed
reciprocal means for turning said valve, and
releasable means for holding the valve in
various positions.
4. In a blow pipe, a valve casing having
20 a series of three superimposed passages
therein, a rotary valve in said casing adapted
to close said passages, said valve being
formed with parallel ports adapted to open
25 a pair of the passages and formed with a
second pair of ports extending on an angle
to the plane of the first named ports
adapted to open the other passages and
form a communication between the other passages,
30 a nozzle embodying a series
of ducts connecting with said passages,
a reciprocal slide bar, a spring acting
on said slide bar to move same in one direc-

tion, means whereby movement of said slide
bar will effect rotation of the valve, and
means for holding said slide bar in various 35
positions in opposition to said spring.

5. In a blow pipe, a nozzle comprising an
outer duct, an inner duct, and an intermediate
duct; a valve casing on which said
nozzle is mounted, means for delivering a 40
combustible gas, air, and oxygen separately
to said valve casing, and a valve in said cas-
ing adapted to direct gas and air to the
outer and intermediate ducts respectively or
direct the gas and oxygen to the interme- 45
diate and inner ducts respectively.

6. In a blow pipe, a valve casing, a valve
therein, a nozzle projecting from said valve
casing, a hand-hold encompassing said valve
casing, a slide bar, a finger piece on said 50
slide bar adapted to be engaged by the finger
of the hand grasping the hand-hold, a
spring for yieldably opposing movement of
the slide bar in one direction and for mov-
ing it in the opposite direction, means where- 55
by movement of said slide bar will effect
movement of the valve, a trip lever for
holding the slide bar in various positions in
opposition to said spring, and means oper-
able by the hand grasping the hand-hold 60
for releasing said trip lever to permit move-
ment of the slide bar under action of said
spring.

ALBERT E. KING.
